UNITED STATES PATENT OFFICE.

EDWARD R. HEWITT, OF MIDVALE, NEW JERSEY, ASSIGNOR TO INTERNATIONAL MOTOR COMPANY, OF NEW YORK, N. Y., A CORPORATION OF DELAWARE.

FUEL PUMP FOR SOLID INJECTION OTTO-CYCLE ENGINES.

Application filed June 28, 1927. Serial No. 202,061.

The present invention relates to pumps for supplying a fluid at a suitable pressure and to be used in measured quantities. More particularly, the invention is adapted for use in constructions where the fluid is to be delivered with an impact blow, periodically, and in measured quantities.

In internal combustion engines, particularly of the Diesel type, it has been found desirable to inject the liquid fuel directly into the cylinder or combustion space by means of a blow effect on the liquid supply column. Although many devices have been designed to utilize this principle in a practical way, great difficulty has been encountered in providing a means to supply the fuel under such an impact, in measured quantities which may be varied as desired.

An object of the present invention is to provide a fuel pump which is constructed to impart a hammer blow upon a confined column of fuel periodically in accordance with the number of revolutions per minute of the engine supplied, the force and suddenness of the blow being independent of the speed of the engine.

A further object of the invention is to provide a pump of the above character which is constructed to enable the quantity of fuel pumped to be varied as desired to effect desired conditions of operation.

It will be apparent as the description proceeds that the pump is readily adapted for use with many types of engines, since it can supply any desired number of independent cylinders with a separate and measured quantity of fuel in a predetermined time relation to the times of supply of the other cylinders of the engine.

Reference will now be had to the accompanying drawings for a more detailed description of the invention, wherein:

Figure 1 is an end elevation of the pump which constitutes a preferred embodiment of the present invention.

Figure 2 is a section taken on line 2—2 of Figure 1 and looking in the direction of the arrows.

Figure 3 is a section taken on line 3—3 of Figure 2 and looking in the direction of the arrows.

Figure 4 is a section taken on line 4—4 of Figure 1 and looking in the direction of the arrows.

Figure 5 is a fragmentary view showing the check valves in detail.

Referring particularly to Figures 1 and 4, a designates a housing which may form a part of, or be clamped to an engine or other driving unit with which the present invention is to be used. Within this housing is carried a drive shaft a' which is driven through a gear a^2 and journaled at one end, as at a^3 , to the housing a . On the outer side of the bearing a^3 , is provided a pinion a^4 which engages a driving gear a^5 mounted on a shaft b , which is carried in the main pump casing.

A suitable clutch connection between gear a^5 and shaft b may be provided which consists of interengaging collars a^6 and b' , the latter being keyed to shaft b , and urged into engagement with collar a^6 by means of spring b^2 seated on nut b^3 . The shaft b is mounted in a suitable packing joint b^4 of well known construction, the entire joint and bearing being carried by a closure b^5 for the main pump casing.

A pump casing c , which may serve as an oil reservoir, is provided with a flanged facing c' over which a cap c^2 is fitted and secured by bolts c^3 . Shaft b is journaled in this cap at c^4 , and in this manner the driving connection for shaft b is completely enclosed. The other end of this shaft may be encased by means of a cap c^5 , and in this manner the structure is completely enclosed. Shaft b carries a number of drop cams b^6 , the number being determined by the number of cylinders in the unit with which the invention is to be used, and these cams are constructed, as their name implies, with shoulders b^7 so that the member lifted thereby will drop off of the shoulders with a speed which is independent of the rotation of the cam. By controlling the force with which the feed is supplied by means of this type of cam, the character of the fuel supply will not be affected by the rotation of the engine, a uniform vaporization and quantity being supplied at all speeds.

The casing c is provided with a closure d which has formed thereon a block d' having a downwardly projecting member d^2 . Formed in the block d' are a plurality of cylinders d^3 in which reciprocates pistons d^4 . The stroke of these pistons carries them beyond the supply ducts d^5 and as they move into the upper portions of the cylinders and cut off the communication of the supply ducts

with such portions, they confine a quantity of fluid, a continued movement of the piston forcing such quantity through the discharge port d^6 . Into the discharge port d^6 is inserted a check valve h comprising a hollow fitting formed with a nipple h' and female threads h^2 . A flange h^3 on the nipple h' seats a valve plunger h^4 under pressure of a spring h^5 . This spring is seated, at one end, on internal shoulder h^6 of the plunger and, at the other end, on the outer face of the flange h^3 on the adjacent fitting h . In the end of the plunger, openings h^7 are provided to permit the fluid to flow therethrough to the next fitting when the plunger is unseated under the pressure of the fluid. Far greater efficiency is obtained by using two checks in tandem since a temporary incapacity of one is supported by the other check to insure no back leakage and the desired pressure in the supply line may be sustained with comparative ease. Each piston is connected by a suitable link e with a coil spring e' , the tension of which is varied by means of suitable adjusting nuts e^2 , these nuts being mounted in the bottom of the closure member d . A stop bar f is mounted so that all the pistons pass therethrough, and movement of the bar is constrained to the plane of the pistons by means 30 of rods f' sliding within the block d' . The position of the stop bar is adjusted in the following manner. A rock shaft g , rotatably mounted in block d' and adapted to be adjusted angularly by means of control lever g' , is 35 provided with eccentrics g^2 . Links g^3 connect rock shaft g with stop bar f through the eccentrics and it will be apparent that the angular position of g' determines the position of stop bar f and consequently, the extent 40 of upward movement permitted the pistons d^4 .

Arms h are mounted pivotally in extension d^2 and bear upon the surface of the cam b^8 , there being one arm for each cam. At the remote ends of these arms, they are pivotally connected to the links e and in this manner, when the arms h ride up on the shoulders b^7 , the springs e' will be compressed. As they ride off the shoulder the spring will force the pistons d^4 upwardly confining and striking an unimpeded blow upon a quantity of fluid within the upper portion of the cylinders d^3 , and forcing the same quantity through the check valves h . By lowering the stop bar f , the extent to which the pistons d^4 enter the upper portion of the cylinders d^3 , is decreased, and a smaller volume of fluid is pumped. The hammer blow imparted to the column by the springs e' forces the fluid through the check valves h under excessive pressure building up a great pressure in the supply line between the check valves and the pressure of the injector spring and enabling it to be finally atomized in the combustion chambers 65 by a suitable form of injector. As previ-

ously noted, the force with which this hammer blow is given depends upon the compression of the springs e' . As the drop from the shoulders of the cams b^7 is not impeded, the suddenness of the hammer blow as well as 70 its force is independent of the speed of rotation of the shaft b and therefore, the speed of the engine. By having an articulated hammer, that is, forming the piston, arms, links, etc. as a unit, advantage is taken of 75 their added inertia and a more powerful blow results. At the extreme end of the stroke, the force of the piston is cushioned by the fluid between the stop bar and the washers e^3 . This column of fluid serves as a cushion 80 to absorb the impact of the moving parts and effectively protects the mechanism. 85

Obviously, the specific construction, design, and arrangement of elements may be varied without departing from the scope of the invention as defined in the appended claims.

What I claim is:

1. An apparatus of the class described comprising a cylinder, an inlet in the side wall of the cylinder to feed fluid thereto from a source of supply, an outlet from the cylinder at a distance from said inlet, a piston in the cylinder adapted to move in its fluid impelling stroke to close the inlet and subsequently move beyond it, a spring to thus move the piston to force fluid through the outlet, and a cam to withdraw the piston and store energy in the spring, said cam being formed with a drop permitting the spring to cause the piston to strike a hammer blow upon the fluid, 95 regardless of the speed of rotation of the cam.

2. An apparatus of the class described comprising a fluid supply, a cylinder, a piston therein, a delivery pipe, a spring to move the piston to force a quantity of the fluid through a delivery pipe, means to vary the tension of the spring, means independent of the first-named means to vary the stroke of the piston, and a cam to withdraw the piston and store energy in the spring, said cam being formed 100 to permit free functioning of the spring regardless of the speed of rotation of the cam.

3. An apparatus of the class described comprising a fluid supply, a plurality of cylinders, a plurality of pistons in the respective cylinders, a delivery pipe, common means adapted to vary the strokes of the pistons equally and simultaneously, separate springs to move the pistons to force a quantity of fluid through the delivery pipe, a plurality of cams to withdraw the pistons and store energy in the springs, and common means to drive the cams to operate the pistons in a predetermined time relation, said cams being formed to permit free functioning of the springs regardless of 115 the speed of rotation of the cams.

4. An apparatus of the character described comprising a casing formed of two parts, one part being a closure for the other, a shaft mounted in the second part, a drop cam car- 120

ried by the shaft, a cylinder carried by the closure, a piston operating in the cylinder, means co-operating with the piston and cylinder to pump a fluid through a delivery system, 5 a spring carried by the closure and normally urging the piston into its pumping stroke, and means to operate the spring from the drop cam.

5. An apparatus of the character described 10 comprising a casing formed of two parts, one part being a closure for the other, a shaft mounted in the second part, a drop cam carried by the shaft, a cylinder carried by the closure, a piston operating in the cylinder, 15 means carried by the closure for varying the stroke of the piston, means co-operating with the piston and cylinder to pump a fluid through a delivery system, a spring carried by the closure and normally urging the piston 20 into its pumping stroke, and means to operate the spring from the drop cam.

6. An apparatus of the character described comprising a casing formed of two parts, one part being a closure for the other, a shaft 25 mounted in the second part, a drop cam carried by the shaft, a cylinder carried by the closure, a piston operating in the cylinder, ducts co-operating with the piston and cylinder to pump a fluid from the casing through 30 a delivery system, a spring carried by the closure and normally urging the piston into its pumping stroke, and means to operate the spring from the drop cam.

7. An apparatus of the character described 35 comprising a casing to contain a supply of fluid to be pumped, pumping means within the casing, a shaft mounted in the casing and carrying a cam to operate the pumping means, a cap co-operating with one end of the casing to form a chamber to enclose a driving connection for the shaft, a housing secured to the casing, means to journal a drive shaft in the housing, said housing co-operating with the cap to complete the closure for the 40 driving means, and means carried within the cap to connect the two shafts operatively, whereby the drive for the pump is completely enclosed.

8. An apparatus of the character described 50 comprising a casing formed of two parts, one part being a closure for the other, an inwardly projecting block carried by the closure, a cylinder formed in the block, a piston in the cylinder, a spring normally urging the piston within the cylinder, an arm pivoted to the block and connected with the piston, and a drop cam mounted in the second part of the casing to engage the pivoted arm.

9. An apparatus of the character described 55 60 comprising a casing formed of two parts, one part being a closure for the other, an inwardly projecting block carried by the closure, a cylinder formed in the block, a piston in the cylinder, means carried by the block to vary the stroke of the piston, a spring normally 65

urging the piston within the cylinder, an arm pivoted to the block and connected with the piston, and a drop cam mounted in the second part of the casing to engage the pivoted arm. 70

10. An apparatus of the character described comprising a casing formed of two parts, one part being a closure for the other, an inwardly projecting block carried by the closure, a cylinder formed in the block, a piston in the cylinder, a stop bar for the piston, means carried by the block to vary the position of the bar and in this manner the stroke of the piston, a spring normally urging the piston within the cylinder, an arm pivoted to the block and connected with the piston, and a drop cam mounted in the second part of the casing to engage the pivoted arm. 75 80

11. An apparatus of the character described comprising a casing formed of two parts, one part being a closure for the other, an inwardly projecting block carried by the closure, a cylinder formed in the block, a piston in the cylinder, a stop bar for the piston, a rock shaft carried by the block means to vary the angular position of the rock shaft, eccentrics on the rock shaft, links connected to the stop bar and rock shaft through the eccentrics to vary the position of the bar and in this manner the stroke of the piston, a spring normally urging the piston within the cylinder, an arm pivoted to the block and connected with the piston, and a drop cam mounted in the second part of the casing to engage the pivoted arm. 90 95 100

12. An apparatus of the character described comprising a casing formed of two parts, one being a closure for the other, a block mounted in the casing, a cylinder formed in the block, a piston in the cylinder, a spring normally urging the piston within the cylinder, an arm pivoted to the block and connected with the piston, and a drop cam mounted in the second part of the casing to engage the pivoted arm. 105 110

13. An apparatus of the character described comprising a casing formed of two parts, one being a closure for the other, a block mounted in the casing, a cylinder formed in the block, a piston in the cylinder, means mounted in the casing to vary the stroke of the piston, a spring normally urging the piston within the cylinder, an arm pivoted to the block and connected with the piston, and a drop cam mounted in the second part of the casing to engage the pivoted arm. 115 120

14. An apparatus of the character described comprising a casing formed of two parts, one being a closure for the other, a block mounted in the casing, a cylinder formed in the block, a piston in the cylinder, a stop bar for the piston, means carried in the casing to vary the position of the bar and 125 130

in this manner the stroke of the piston, a spring normally urging the piston within the cylinder, an arm pivoted to the block and connected with the piston, and a drop cam mounted in the second part of the casing to engage the pivoted arm.

15. An apparatus of the character described comprising a casing formed of two parts, one being a closure for the other, a block mounted in the casing, a cylinder formed in the block, a piston in the cylinder, a stop bar for the piston, a rock shaft mounted in the casing, means to vary the angular position of the rock shaft, eccentrics on the rock shaft, links connected to the stop bar and rock shaft through the eccentrics to vary the position of the bar and in this manner the stroke of the piston, a spring normally urging the piston within the cylinder, an arm pivoted to the block and connected with the piston, and a drop cam mounted in the second part of the casing to engage the pivoted arm.

16. An apparatus of the character described comprising a casing formed of two parts, one part being a closure for the other, an inwardly projecting block carried by the closure, a plurality of cylinders formed in the block, pistons in the cylinders, independent springs for each piston normally urging the respective pistons inwardly, a plurality of arms pivoted to the block and connected with the respective pistons, a shaft mounted in the second portion of the casing, a plurality of cams spaced angularly on the shaft and engaging the respective pivoted arms, a stop bar through which the pistons move, guides slidably mounted in the block to constrain the movements of the bar, a rock shaft carried by the block, means to vary the angular posi-

tion of the rock shaft, eccentrics on the rock shaft, and links connected to the stop bar and rock shaft through the eccentrics to vary the position of the bar to control the strokes of the pistons.

17. An apparatus of the character described comprising a casing formed of two parts, one being a closure for the other, a block mounted in the casing, a cylinder formed in the block, a confined portion of the cylinder leading to a discharge port, an unconfined portion of the cylinder, a piston therein, an intervening space between the confined portion and the unconfined portion communicating with the interior of the casing, means mounted in the casing to vary the travel of the piston into the confined portion, a spring normally urging the piston within the cylinder, an arm pivoted to the block and connected with the piston, and a drop cam mounted in the second part of the casing to engage the pivoted arm.

18. An apparatus of the character described comprising a casing formed of two parts, one being a closure for the other, a block mounted in the casing, a cylinder formed in the block, a piston in the cylinder, means mounted in the casing to vary the stroke of the piston, a spring normally urging the piston within the cylinder, an arm pivoted to the block and connected with the piston, a drop cam mounted in the second part of the casing to engage the pivoted arm, and means to cushion the force of the piston and associated parts.

This specification signed this 16th day of June, A. D. 1927.

EDWARD R. HEWITT.
